UNITED STATES PATENT OFFICE.

RALPH L. JONES, OF GORDON, TEXAS.

SLING-SHOT.

1,346,754.

Specification of Letters Patent.

Patented July 13, 1920.

Application filed March 23, 1920. Serial No. 368,131.

To all whom it may concern:

Be it known that I, RALPH L. JONES, a citizen of the United States, residing at Gordon, in the county of Palo Pinto and State 5 of Texas, have invented new and useful Improvements in Sling-Shots, of which the following is a specification.

This invention relates to shooting devices and has for its object the provision of an 10 improved sling shot which may be used as an amusement device for projecting pebbles and the like and which may be made suitable for actual utility in shooting.

The device is somewhat in the nature of 15 the well known sling shot commonly used by youths in which the propelling means is ordinarily the elasticity of a heavy rubber band with which is connected the sling within which the pebble or other missile is 20 placed.

An important object of the present device is the elimination of rubber bands as propelling means and the utilization of coil 25 springs in their place, the structure being thereby rendered more durable, the efficiency being greatly increased and the liability of breakage being greatly reduced.

With the above and other objects and advantages in view, the invention consists in 30 the details of construction to be hereinafter more fully described and claimed, and illustrated in the accompanying drawings in which—

Figure 1 is a front elevation of the device, 35 Fig. 2 is a side elevation, and Fig. 3 is a horizontal sectional view.

Referring more particularly to the drawings, the numeral 10 designates the frame of the device which includes a U-shaped upper 40 portion and a handle extending downwardly therebelow. As shown, this frame in actual practice, is shown as being formed of a central member 11 at the sides of which are disposed upstanding members 12 which extend 45 above the upper end of the central member 11 to provide horns 13. The central member 11 extends below the lower ends of the members 12 to provide a handle 14 which preferably has its edges rounded. Transverse bolts 15, provided with nuts 16, extend 50 through the side members 12 and through the central member 11 whereby to provide a strong and rigid structure.

Secured upon and extending from one 55 side of the horns 13, are cylindrical housings 17 within the bores of which are dis-

posed coil springs 18 and the inner ends of these housings are closed except for relatively small holes 19. The connection of the housings 17 with the horns 13 might be 60 formed in a variety of ways though in the present instance each housing is shown as formed with a reduced extension 20 fitting within a hole 21 in the horn.

Extending through each spring 18 is a rod 65 or wire 22 which carries at one end a disk 23 engaging against the outer end of the spring 18 and which has its other end formed with an eye 24. Washers 25 are disposed on the second mentioned ends of the 70 rods or wires for preventing them from slipping into the extension 20 of the housings. Connected with the eyes 24 are flexible members 26 which are preferably cords and these are connected with a sling 27 75 formed of leather or other suitable material.

In the operation of the device, the operator places the pebble or other missile within the sling 27, grasps the sling from opposite sides whereby to hold it firmly in engagement with the missile, it being understood that the handle 14 of the frame is held in the other hand. The operator then pulls back upon the sling and missile which results in pulling upon the cords 26 and rods or wires 22 80 and this causes compression of the springs 18. When the operator has aimed the device and releases his grip upon the sling and missile, it is apparent that the springs 18 will fly rapidly to their normal positions which 85 will result in jerking the cords and sling very quickly and this will result in the missile being projected between the horns 13.

From the foregoing description and a study of the drawings it will be apparent 90 that I have thus provided a very simply constructed and consequently inexpensive sling shot which will be powerful in action, which will not be likely to break, and which will be highly entertaining in use.

While I have shown and described the preferred embodiment of my invention, it is of course to be understood that I reserve the right to make such changes in the form, construction, and arrangement of parts as 95 will not depart from the spirit of the invention or the scope of the subjoined claims.

Having thus described my invention, I claim:

1. A device of the character described 110 comprising a frame having its upper portion of U-shape and having a handle at its lower

- portion, cylindrical housings extending from one side of the frame at the upper end thereof, a coil spring disposed within each housing, a rod extending through each 5 spring and provided at one end with an eye, a disk upon the other end of each rod engaging against one end of the spring, cords connected with said eyes, and a sling connected with said cords.
- 10 2. A device of the character described comprising a frame including a central member, side members secured thereto and extending thereabove whereby to define horns, cylindrical housings secured to and 15 extending from said horns at one side thereof, the forward ends of said housings being closed and provided with small holes, coil springs within said housings and abutting against the closed ends thereof, rods extend-

ing through said holes and provided at their 20 forward ends with eyes, said rods extending longitudinally through said springs, disks carried by the far ends of said rods and engaging against the other ends of the springs, cords connected with said eyes, and a sling 25 carried by said cords.

3. A device of the character described comprising a U-shaped frame having a handle, rods slideable through the arms of said frame, stop members on the ends of said 30 rods, coil springs surrounding the rods and abutting against the stop members whereby to urge the rods in one direction, flexible members connected with the other ends of said rods, and a sling connected with said 35 flexible members.

In testimony whereof I affix my signature.
RALPH L. JONES.
